(57) **CLAIM**

The ornamental design for a flat tire trolley as shown and described.

DESCRIPTION

FIG. 1 is a top front perspective view of a flat tire trolley showing my new design;

FIG. 2 is a front view of the design of FIG. 1;

FIG. 3 is a rear view of the design of FIG. 1;

FIG. 4 is a right side view of the design of FIG. 1;

FIG. 5 is a left side view of the design of FIG. 1;

FIG. 6 is a top view of the design of FIG. 1;

FIG. 7 is a bottom view of the design of FIG. 1;

FIG. 8 is top rear perspective view of the design of FIG. 1; and,

FIG. 9 is bottom perspective view of the design of FIG. 1 showing a front component rotated to an alternate position as may occur during use.

The broken lines in the figures show portions of the flat tire trolley that form no part of the claimed design.
